UNITED STATES PATENT OFFICE.

THEODORE W. NYGREEN, OF BELLINGHAM, WASHINGTON, ASSIGNOR OF ONE-FOURTH
TO JOHN WALKER, OF BELLINGHAM, WASHINGTON.

CARRIER APPARATUS.

1,364,404.

Specification of Letters Patent.

Patented Jan. 4, 1921.

Application filed September 5, 1919. Serial No. 321,766.

To all whom it may concern:

Be it known that I, THEODORE W. NYGREEN, a citizen of the United States, residing at Bellingham, in the county of 5 Whatcom and State of Washington, have invented a new and useful Carrier Apparatus, of which the following is a specification.

The present invention relates to carrier apparatus, one of its objects being to provide an apparatus of this character especially designed for use in coal mines to convey coal therefrom, the construction being such as to facilitate the handling of the coal and save time and labor.

15 A further object of the invention is to provide a pneumatic carrier apparatus wherein the source of pneumatic force serves also as a means to ventilate the mine.

It is a further object of the invention to 20 provide a carrier apparatus wherein a number of spherical receptacles or carriers are provided, the carriers being provided with locking means of novel form.

Another object of the invention is to provide 25 a carrier apparatus which is simple in construction, consists of few parts, and may be manufactured and sold at low cost.

With the above and other objects and advantages in mind, the invention consists of 30 the construction and arrangements of parts, which will be hereinafter set forth in the appended claim, the invention being illustrated in the accompanying drawings, wherein—

35 Figure 1 is a diagrammatic view of the apparatus;

Fig. 2 is a fragmentary sectional view through the carrier illustrating the lock construction thereof;

40 Fig. 3 is a side elevation of the carrier;

Fig. 4 is an enlarged section through a portion of the container and part of the door or closure engaging the same.

45 Fig. 5 is an elevation of the inner face of the bolt operating disk carried by the door or closure of the container, the pin engaged by the disk being shown in section.

As illustrated in the drawing only the discharged end of the conduit 5 is shown, it being 50 obvious that this conduit extends throughout the mine and is provided with receiving stations at the various beds of the mine.

The conduit 5 terminates in a downwardly

curved end which will break the force of the carriers passing through the conduit. A door 6, which is normally closed, is hinged to the lower end of the conduit and is only opened when the carriers strike the same. A cage 7 receives the ends of the conduit and is supported in any desired manner. The forward end of this cage is open and is provided with a door 8 hinged as at 9 to the upper edge of the cage. A branch conduit 10 leads from the conduit 5 above the curved end and communicates with a fan housing 11 in which is mounted a fan 12 the purpose of which is to produce a suction in the conduit 5. The shaft of the fan is supported in bearings 13 disposed on the side of the housing 11, the shaft being provided with a drive pulley 14.

There are provided a number of hollow spherical receptacles adapted to be drawn through the conduit 5 by the suction produced therein and thence to the cage 7. Each of these containers 15 is provided with a door opening 16 and at the inner edge thereof an outstanding rim 17 is provided and adapted for engagement with outstanding lugs 19 formed at one transverse edge of the door 18. Thus the door 18 is capable of pivotal movement.

A lock of special construction is used in connection with a door and consists of a casing 20 secured to the inner face of the door 18. Slidably mounted in a guide 21 in the casing 20 is a bolt 22 adapted for engagement with the rim 17.

Rotatable in an opening 28 in the door 18 and in the casing 20 is a disk 24 provided with an eccentric or spiral groove 25 in its outer face in which is disposed a pin 26 carried by the bolt 22. A socket 27 is formed in the disk 24 and is adapted to be engaged by a wrench when it is desired to retract or project the bolt 22. It will be obvious that upon rotating the disk 24, in one direction the bolt will be retracted within the casing 20 and that upon rotating the same in the opposite direction the bolt will be projected into engagement with the rim 17.

Deflecting bars 30 located across the point of intersection of the conduits 5 and 10, act as a deflector to direct the containers 105 across the end of the conduit 10.

This embodiment of the invention is illustrative only and it will be understood that

the same may be modified in many respects and that such limits of modification are only governed by what is claimed.

What is claimed is:

5. In carrier apparatus the combination with a suction conduit, and a suction element in communication with the conduit, of a downwardly offset curved terminal extending from the conduit and having an inclined 10 end, a cage housing said end and having an inclined free end, gravity seated doors mounted upon the free ends of the flue terminal and of the cage, and a spherical con-

tainer movable by suction within the flue and by gravity within the curved offset terminal and through the cage, said doors being movable to open position by the pressure of the container thereagainst.

In testimony that I claim the foregoing as my own, I have hereto affixed my signature in the presence of two witnesses.

THEODORE W. NYGREEN.
